UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

TELEPHONE TOLL-INDICATOR.

SPECIFICATION forming part of Letters Patent No. 733,494, dated July 14, 1903.

Application filed December 3, 1902. Serial No. 133,747. (No model.)

To all whom it may concern:

Be it known that I, GEORGE A. LONG, a citizen of the United States, and a resident of Hartford, in the county of Hartford and State 5 of Connecticut, have invented certain new and useful Improvements in Telephone Toll-Indicators, of which the following is a specification.

My improvement relates to the class of devices employed in connection with telephones that are used for the purpose of indicating both audibly and visually the fact that certain acts required for the use of the instrument have been performed; and the object 15 of my invention is to provide a device of this class that shall be simple and effective in construction and operation and slight in appearance and one in which the chances of fraudulently indicating that the requirements 20 for the use of the apparatus have been complied with shall be eliminated. A form of device in which these objects may be attained is illustrated in the accompanying drawings, in which—

25 Figure 1 is a view in side elevation of my improved device with the case cut in section, the parts being in normal position of rest. Fig. 2 is a like view, but showing the parts in the position with the plunger pushed downward to its farthest limit. Fig. 3 is a front view of the device with the hammer and case removed. Fig. 4 is a top view of the device with the case removed. Fig. 5 is a view in side elevation of the parts from the opposite 30 side of the view of Fig. 1. Fig. 6 is a view in section through the plunger.

In the accompanying drawings the numeral 1 indicates the base of the apparatus, that is provided with means, as screw-holes and 40 screws, for attachment to the back board of a telephone apparatus. A case 2 is attached to the base, preferably removably secured thereto and of proper size and shape to contain the operating mechanism. An opening 45 3 is formed through the case, into which the face of a register 4 projects and through which the numerals on the register may be observed. A standard 5 is mounted on the base, prefer-

ably formed integral therewith, and the register 4 is secured to this standard. A projection 6 extends upward from the base and is preferably formed integral therewith. 50

A gong 7 is secured to the standard 5 and rests as to a portion of its surface close to the projection 6, but not touching the projection 55 when allowed to assume its normal position.

A hammer-lever is pivoted to the side of the standard 5, and this includes a hammer-arm 8 and a spring-arm 9. A hammer 10 is borne on the end of the arm in position to 60 strike the gong 7, and a hammer-spring 11 is attached to the spring-arm at one end and the other end to a muffler-arm 12.

A muffler-lever is mounted on a post 14, rising from the base, and this lever includes 65 the spring-arm 12, a muffler 13, and a muffler-actuating arm 15. The muffler 13 in the normal position of the parts rests against the side of the gong 7 and presses it against the projection 6 on the base of the device. 70

A guide-post 16 is secured to the base, and a pin 17 from the plunger 18 projects into a central opening in this guide. This plunger has a recess 19 located between the pin and the inner wall of the opening in the bottom of 75 the plunger, this recess containing one end of the plunger-spring 20, that surrounds the guide 16 and the pin 17. This plunger has a rigid bearing 21, adapted to press against the edge of the standard 5, and also a cam 22 for actuating the muffler-lever. The plunger also bears a trip 23, having a notch 24, adapted to engage a trip-pin 25 on the hammer 10. This trip is pivoted to the plunger, and a trip-spring 26 thrusts against the edge of the trip, 80 forcing its free end outward from the plunger. The plunger also bears a register-operating pin 27, which engages a slot in the register-arm 28, secured to the shaft 29 of the register. The register is of the kind known 85 as a "ratchet-operated" register of ordinary construction, and further description is deemed unnecessary herein.

In the operation of the device the parts are in the relative position shown in Fig. 1, with 90 the trip 23 in engagement with the pin 25 and

the muffler 13 resting against the gong and clamping the latter against the projection 6 under the pull of the spring 11. The plunger being pushed down, the engagement of the 5 trip with the trip-pin 25 forces the hammer away from the gong, this movement carrying the free end of the trip away from the plunger. A stop 30 on the back of the trip engages the side of the plunger and prevents forward 10 movement of the free end of the trip. Further downward movement disengages the trip from the trip-pin 25, and the hammer is forced against the gong by the pull of the spring 6. Just before the hammer is freed 15 from engagement with the trip the cam 22 on the lower end of the plunger engages the muffler-arm 15, swinging the muffler-lever and throwing the muffler away from the gong. The muffler is held away from the gong until 20 the upward movement of the plunger releases the lever, when the muffler is again thrown against the gong, clamping it between the muffler and the projection 6 from the base. Further upward movement of the plunger 25 again causes the trip to engage the trip-pin 25, thus resetting the parts. The downward movement of the plunger through the engagement of the pin 27 with the slot in the register-arm moves the register forward a 30 unit space, the return movement of the plunger carrying the arm backward in position to again operate the register.

It will be noted that the muffler in the normal position of the parts clamps the gong between the muffler and the projection from the 35 base, and it is therefore impossible to sound the gong, as by a sharp blow delivered on the outside of the case inclosing the mechanism, as is possible in prior devices where the gong 40 is free to vibrate at all times. It will be noted that the muffler is thrown away from the gong at the time the hammer is released to strike it, and the vibrations of the gong may be continued for any interval desired by holding the 45 plunger depressed. Immediately upon releasing pressure on the plunger the muffler will be thrown against the gong and the vibration thereof stopped.

It is obvious that the details of construction 50 of the device may be varied to a considerable extent and yet embody the main features of the invention, and I do not desire to limit myself to the exact form of construction and mode of operation herein illustrated and described.

55 What I claim as my invention, and desire to secure by Letters Patent, is—

1. In combination in a telephone toll-indicator including a gong and a register, a support for the gong, a plunger operatively connected with the register, a muffler adapted to 60 embrace and clamp the gong, operative connections between the plunger and hammer, the hammer, and connections between the plunger and muffler for operating the latter 65 and disengaging it from the gong during a predetermined movement of the plunger.

2. In combination in a telephone toll-indicator including a gong and a register, a support for the gong, a plunger operatively connected with the register, a trip borne on the 70 plunger and adapted to operate the hammer, the hammer, a muffler-lever coöperating with a complementary muffler member to muffle the gong, and a cam on the plunger adapted to operate the muffler-lever. 75

3. In combination in a telephone toll-indicator including a register, a gong, a support for the gong and a hammer, a projection lying opposite the side of the gong, a lever located on the opposite side of the gong from the projection, and means for operating the register, the hammer and means for throwing the lever away from the projection to release the gong. 80

4. In combination in a telephone toll apparatus including a register, a gong, a support 85 for the gong and a hammer, a muffler comprising a part lying opposite one side of the gong, and a coöperating part located on the opposite side of the gong from the first-named part, and a plunger having means for operating the hammer, the register and one of the muffler parts to release the gong. 90

5. In combination in a telephone toll apparatus including a register, a gong, a support for the gong and a hammer, a plunger having a pin engaging an arm on the register, a swinging trip borne on the plunger and adapted to engage and release the hammer, a cam adapted to operate a muffler arranged to embrace the clamp and gong, and the muffler. 95 100

6. In combination in a telephone toll apparatus including a base and a gong and register mounted thereon, a plunger mounted on the base, a projection from the base lying opposite the side of the gong, a muffler-lever 105 pivoted on the base and lying on the opposite side of the gong from the projection, a pin on the plunger in engagement with the register-arm, a swinging trip mounted on the plunger to operate the hammer, and a cam borne on the plunger to operate the muffler-lever. 110

7. In combination in a telephone toll-indicator including a base and a gong and register mounted thereon, a muffler projection from the base, a swinging muffler mounted 115 opposite the projection on the opposite side of the gong, a swinging hammer-lever and hammer mounted on the base, a plunger having a pin engaging a register-arm, a swinging trip mounted on the plunger and adapted to engage the hammer, and a cam located on the plunger and adapted to actuate the muffler-lever. 120

8. In a telephone toll-indicator, in combination with a gong and a hammer for operating the gong, a gong-support, a muffler adapted to embrace and clamp the gong in the normal position of the parts, and means for actuating the muffler. 125

9. In a telephone toll-indicator, in combination with a gong and a hammer for operating the gong, a gong-support, a muffler adapted 130

to embrace and clamp the gong in the normal position of the parts, and a plunger adapted to operate the hammer and the muffler.

10. In a telephone toll-indicator, in combination with a gong, a hammer for operating the gong, a support for the gong and a register, a muffler adapted normally to embrace and clamp the gong, and a plunger operatively

connected with the hammer, the muffler and the register for operating them at predetermined intervals.
